UNITED STATES PATENT OFFICE.

NATHAN BAUML, OF FOXBORO, MASSACHUSETTS.

SASH FASTENER.

Application filed February 19, 1925. Serial No. 10,258.

To all whom it may concern:

Be it known that I, NATHAN BAUML, a citizen of the United States, residing at Foxboro, in the county of Norfolk and State of Massachusetts, have invented certain new and useful Improvements in a Sash Fastener, of which the following is a specification.

This invention relates to an improved fastener which is especially designed for use in connection with window sashes, although it is capable of use in connection with other forms of closures.

The invention relates more particularly to a fastener which is in the form of a cam block against which one sash is adapted to wedge to prevent movement of the same in a predetermined direction, this block being mounted upon the complementary sash and there being novel spring tension coacting means between the mounting means and the block to resiliently maintain the block in operative position.

The features and advantages derived from the particular construction employed for carrying the inventive conception into effect will become apparent from the following description and drawing.

In the accompanying drawing forming a part of this application and in which like numerals are employed to designate like parts throughout the same:—

Figure 1 is a fragmentary elevational view of a pair of window sashes showing the improved fastener carried by the upper sliding sash.

Figure 2 is a section taken approximately on the plane of the line 2—2 of Figure 1.

Figure 3 is a perspective view of one of the details, and

Figure 4 is an edge elevation on a reduced scale showing the manner in which the locking action is effected.

Referring to the drawings in detail, the reference character 1 designates generally the upper sliding sash, 2 indicates the lower sliding sash, and 3 the frame in which the sashes are mounted.

The improved fastener comprises primarily a block 4 which is rounded on one side to provide a cam or wedging surface. The opposite side of the block is substantially flat, being formed between its ends with a transverse recess 5. Also at the center of the block are bolt holes or the like 6. Seated in the recess 5 is a plate 7, the upper and lower edges of which are directed lat-

erally as at 8 to provide flanges. This plate is bolted or otherwise secured in place and one edge thereof extends beyond the outer vertical edge as shown in Figure 1, this extended edge being provided with upper and lower elongated slots 9 and with an intermediate tongue 10. For mounting the device upon the upper sash 1 on one of the rails thereof I provide an attaching plate 11 fastened in place by screws or the like 12. This plate is provided with extended arms 13, the free ends of which are rolled or curled as at 14 to provide pivotal connections with the slotted portions 9 of the extension on the plate 7. In other words, the end of the arms 13 are extended through the elongated slots and then bent around to provide pivot knuckles. Between the arms 13 and the attaching plate 11 is a spring tongue 15 for coaction with the first named tongue 10. The two tongues constitute what may be termed a snap fastener, the approximate relation of the tongues is also shown in Figure 2.

Normally, the tongues 10 and 15 are in the overlapping relation shown in Figures 1 and 2 wherein the wedge block 4 is disposed in spaced relation to the window pane. This is the ineffective position of the device. However, by swinging the block in a direction from right to left upon the pivots and disposing it in the dotted line position indicated in Figures 1 and 2, a snap action will be produced through the medium of the coacting tongues to resiliently maintain the block in this position. Assuming that the device is fastened to one of the rails of the upper sash, about six inches or so above the bottom rail of the sash, it is obvious that the block will have its cam surface disposed in the path of movement of the top rail of the lower sash as shown in Figure 2. Hence, outward movement of the lower sash is prevented. The further the lower sash is lifted, the greater the wedge action.

With the device thus disposed, the upward movement of the lower sash is limited and it is obvious that the same may be left open with safety. In this connection it is to be pointed out that the fastener will be disposed at a point to stop the movement of the lower sash so that the opening produced thereby will be such as to prevent the entrance of an intruder therethrough. With the device in its normal position shown in Figure 1, it does not interfere with the usual

movement of the sashes, proper clearance being provided.

It is thought that the foregoing description taken in connection with the accompanying drawing will enable persons skilled in the art to which the invention relates to obtain a clear understanding of the same. Therefore, a more lengthy description is thought unnecessary.

10 Although the preferred embodiment of the invention has been shown and described, it is to be understood that minor changes coming within the field of invention claimed may be resorted to if desired.

15 Having thus described the invention, what I claim is:—

1. A sash fastener of the class described comprising a block, one surface of which is rounded to provide a wedging cam for a lower sliding sash, an attaching plate adapted to be fastened to an upper coacting sash, and resilient snap retaining means between the plate and the block.

2. A sash fastener of the class described comprising a retaining member, a plate attached thereto, an attaching plate, a pivotal connection between said plates, and coacting spring tongues carried by the plate and cooperable to produce a snap fastener. 25

3. A sash fastener comprising a retaining block having one surface rounded to provide a friction cam, a plate attached to the opposite side of said block, said plate having an extended portion formed with elongated slots and with an intervening tongue, an attaching plate adapted to be mounted upon a relatively stationary part, said attaching plate embodying arms, the free ends of which are extended through said slots to provide a pivotal connection between said plates, the attaching plates being formed between said arms with an intervening resilient tongue cooperable with the first named tongue. 30 35 40

In testimony whereof I affix my signature.

NATHAN BAUML.
